UNITED STATES PATENT OFFICE

WALTER TISHAUSER, OF ST. HELENA, CALIFORNIA

MATERIAL STACKING AND VENTILATING DEVICE

Application filed April 26, 1932. Serial No. 607,658.

This invention relates to a novel sectional stacking and ventilating device which is especially, but not necessarily, adapted to facilitate stacking of hay, while at the same time affording a means of protection as to the hay stack and surrounding property.

It is a matter of common knowledge that hay stacks left to dry for curing purposes in the field or barns are subject to detrimental effects and frequently are self destructive due to uncontrollable spontaneous combustion. As a matter of fact, a hay stack is frequently a fire hazard, particularly when located within the vicinity of barns and wooden out-buildings, or in the barns themselves.

The purpose of the present invention is to provide a suitably designed sectional upright which functions as a core and ventilating structure around which the hay may be conveniently and expeditiously built into stack form while it is kept free from fire by effective ventilation.

The specific construction employed for accomplishing the desired results will become more readily apparent from the following description and drawings.

In the drawings:

Figure 1 is an elevational view showing the device located in a conventional hay stack.

Figure 2 is a vertical sectional elevational view thereof removed from the stack.

Figure 3 is a horizontal cross section on the line 3-3 of Figure 1.

Figure 4 is a section taken approximately on the plane of the line 4-4 of Figure 1.

Figure 5 is a detail elevational view of one of the ventilator sections.

Figure 6 is a top plan view of the closing cap.

Figure 7 is a perspective view of a duplex retaining clip serving as a fastener between superposed sections of the device as seen in Figure 4.

The device is made up of two or more substantially duplicate sections one of which may be distinguished as a lower or base section 8, the other one of which may be distinguished as the superposed upper section 9.

These are of all metal construction and of

appropriate diameter and proportion. For example the lower section may be about three feet high, the intermediate sections about two feet, the top sections about one foot to facilitate assembling and disassembling, as well as to expedite handling during the time of shipping. The lower section comprises upper and lower ring like bands 10 and 11 as well as an intermediate band 12, these being of corresponding portions and diameter, and the circumferentially spaced perpendicular upright 13 being riveted or otherwise attached thereto, the lower ends of the upright are bent laterally outward to provide supporting feet 14 and these are apertured to accommodate stakes or suitable anchoring members 15.

The upper section 9 comprises a series of two or more ring like bands. In the form of the invention illustrated I have shown three of these bands distinguished by the numerals 16, 17 and 18 respectively. A circumferentially spaced strap or strip 19 forming the uprights are fastened thereto in such a manner that they terminate flush with the upper edge of the upper ring 16 and having their lower end portion 20 extending below the lower edge of the ring 18 so as to slip down over the ring 10 to interlock the two sections detachably together. This allows the ring 18 to sit down firmly on the ring 10.

Usable in connection with either one or both of the sections 8 and 9 is a closure in the form of a cap 21 which comprises a ring 22 of a diameter corresponding to the ring like band. The numerals 23 and 24 designate upper and lower disks pinned together at their central portions indicated at 25 and having the inturned portions 26, the members 27 are in the form of L-shaped straps whose horizontal portions are fastened to the disks 23 and 24 and whose vertical portions are riveted to the ring 22 and extended below the lower edge of the ring so as to engage over the adjacent top ring of the companion sections 8 or 9 as the case may be. When one section only is used for short stacks, such as for example the section A then the top is attached to the ring 10 whereas when two sections are employed the cap is applied

to the ring 16 as shown in the drawings.

From the foregoing description it will be seen that the ventilator is in the nature of an open work post adapted to be centrally located in the haystack as shown in Figure 1 of the drawings. The various sections are constructed of metal rings and straps joined together to form open work cage like sections whereby to permit the sections to be detachably connected together in vertically superposed relationship to secure the desired rigidity. The cap 21 is applicable to either one or both of the sections to prevent the hay from dropping down into the ventilator and clogging it.

When using two or more sections as seen in the drawings it may be well to provide supplemental means for fastening the sections together and this means may be in the nature of a simple duplex fastener of the type illustrated in Figure 7. This comprises a pair of duplicate bendable metal bars 28 fastened together by a tie cord or wire 29 to facilitate maintenance and guard against accidental loss. These straps are formed of bendable metal so that they may be placed around the rings 10 and 18 as shown in Figure 4. The opposite ends are bent into the form of hooks 30 and 31 thereby facilitating application and removal and insuring a greater rigidity to guard against displacement of the sections of the device after it is assembled in a hay stack.

It is manifest that a device constructed in accordance with the principles of this invention is simple, effective, capable of expeditious installation and handling either during the time of transportation or erection.

It is understood that the invention serves not only as a convenient means in the field for stacking hay but is also advantageous for use within barns and similar buildings. In fact, several of these devices may be installed in a barn with reasonable assurance against fire hazards.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming

within the field of invention claimed may be resorted to if desired.

Having thus described my invention, what I claim as new is:

1. A hay stack ventilator and erecting device of the class described comprising a lower section including upper and lower rings of corresponding diameter, a plurality of vertical metal straps attached to the exterior faces of said ring, the upper ends of the straps being flush with the upper edge of the uppermost ring, the lower ends thereof extending below the lowermost ring and directed laterally outward and apertured for anchoring purposes; and an upper companion section including upper and lower rings together with a plurality of circumferentially spaced vertically extending straps attached to said ring, the rings of said upper section corresponding in diameter to those of the lower section, and the lower ends of the strap members thereof extending below the lowermost ring and fitting down over the upper ring of the lower section and the adjacent rings of said sections being in abutting relationship. 70 80 85 90

2. A hay stack ventilator and erecting device of the class described comprising a lower section including upper and lower rings of corresponding diameter, a plurality of vertical metal straps attached to the exterior faces of said ring, the upper ends of the straps being flush with the upper edge of the uppermost ring, the lower ends thereof extending below the lowermost ring and directed laterally outward and apertured for anchoring purposes; and an upper companion section including upper and lower rings together with a plurality of circumferentially spaced vertically extending straps attached to said ring, the rings of said upper section corresponding in diameter to those of the lower section, and the lower ends of the strap members thereof extending below the lowermost ring and fitting down over the upper ring of the lower section and the adjacent rings of said sections being in abutting relationship, 100 105 110 115 120

In testimony whereof I affix my signature.

WALTER TISHAUSER.
